UNITED STATES PATENT OFFICE.

CHARLES J. PETRASEK, OF NEW LEBANON, NEW YORK.

CEILING-SLEEVE ATTACHMENT.

Application filed May 7, 1923. Serial No. 637,291.

To all whom it may concern:

Be it known that I, CHARLES J. PETRASEK, a citizen of the United States, residing at New Lebanon, in the county of Columbia 5 and State of New York, have invented certain new and useful Improvements in Ceiling-Sleeve Attachments, of which the following is a specification.

This invention relates to steam fitting appliances or the like and has particular reference to what are commonly called ceiling sleeves fitted loosely around steam or hot water pipes so as to serve among other purposes to hold the pipe temporarily in place 15 from lateral movement while the plaster or equivalent finishing devices are applied to the building and also to permit vertical movement of the pipe due to expansion and contraction.

20 In the usual practice the sleeve, of substantially the same general character as the sleeve shown herein, is held in place by means of two or more metal straps attached to its upper end, the straps being extended 25 toward or over the upper edge portions of the adjacent floor beams and there nailed by a workman on the upper floor. Another workman or a helper, however, is required beneath the floor at which the fitting 30 is being done in order to determine as nearly as possible the precise elevation or location of the sleeve. The result is that not only are two men required for this purpose but there is difficulty in determining 35 the proper location for the sleeve with respect to the ceiling plaster that co-operates with it and also to maintain the desired position after it is established due to the fact that any lateral movement of the pipe serves 40 to swing the sleeve upward as well as laterally, around the points of attachment of the metal straps as centers.

45 Among the objects, therefore, of this improvement is to facilitate the placing of the sleeve at any desired distance between the floor beams or relation to either of the adjacent beams and also with respect to the ceiling line or plane; to enable a workman not only to do the work alone, but that he 50 may adjust the sleeve much more reliably than could be done by two men as practised heretofore; to accomplish the result desired with the least expenditure of time and effort on the part of the workman; to provide 55 a construction or fastening means which in

itself constitutes lathing for the direct application of the coating of plaster, and also serving to constitute a support for a filling of concrete or the like between the floor beams or their equivalent when fireproof 60 construction is used.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like 70 reference characters designate the same parts in the several views, and in which—

Figure 1 is a vertical sectional view showing diagrammatically the application of one form of the device. 75

Fig. 2 is an enlarged detail view of the same form of the invention.

Fig. 3 is a plan view of one form of sleeve support.

Fig. 4 is a view similar to Fig. 1, but 80 showing a modification.

Fig. 5 is a horizontal section on the line 5—5 of Fig. 4.

Referring now more specifically to the drawings the sleeve 10 is shown conical or 85 tapered and is of sheet metal, open at both ends according to the diameter of the pipe or riser 11 and so having no clearance as heretofore for collection of dirt, plaster or the like at the top. At the lower end the 90 sleeve 10 is fitted with an ornamental cap 13 attached in any suitable manner and having a more restricted opening 14 fitting fairly close around the pipe and hence of the same diameter as the smaller upper end 95 of the sleeve. This cap or ornament 13 is designed to extend downward below the plaster or finishing material for the ceiling and at the same time its upper edge is intended to mark the plane of the lower surface of the plaster. By my improvement 100 the location of the sleeve and its attached cap is easily determined with respect to the ceiling structure and therefore the cap will always have a uniform appearance or co-operation with the plaster. In the usual constructions it is not uncommon for the plaster to be applied either above the cap or so as to cover more or less of it, making 105 in either event an unsightly finish. From 110

the tapered form of the sleeve it follows that the cap will always lie in a perfectly level position perpendicular to the axis of the pipe.

5 15 indicates a sheet or strip of wire mesh material of any suitable construction, such as woven wire or stamped meshwork such as is suitable for use as metal lathing. This strip is of a length suitable to more than 10 span two adjacent floor beams 16 so that while provided with a hole 17 nearer one end than the other of the strip, the end portions of the strip or support may be fastened to the bottoms of the adjacent beams irrespective of the spacing of the pipe between 15 the beams. Assuming for instance, that the beams are 12 inches between centers the strip 17 should measure approximately 8 inches from one end to the center of the hole 17 20 while the other end portion may be 12 inches long. By this arrangement if the pipe comes midway between the beams, the shorter end of the strip may be nailed directly against the bottom of one beam while the 25 other end portion may pass beyond the other beam and be nailed against one side thereof. On the other hand, if the pipe should come close to one of the beams, the longer end of the strip still would be long enough to reach 30 the remote beam while the shorter end would fasten around the nearer beam as indicated in Fig. 1. While ordinarily the strip 15 is provided with only one hole 17 I indicate at 17' the expedient of forming therein more 35 than one hole for the accommodation of more than one pipe at the same installation. Bounding the hole 17 the sleeve support or strip 15 is provided with a downwardly turned flange 18 through which the sleeve 40 is projected and fastened securely as by rivets 19. The space between the support 15 and the cap may be three-fourths of an inch or thereabouts according to the character of the plaster or other finishing material. The device thus far described is a 45 complete unit and assembled preferably at the factory. In use the sleeve is slipped over the riser at the time the latter is erected, in the usual manner, and when the location of 50 the riser is approximated the workman charged with the duty of making the connections will simply pass the sleeve upward, bringing it into proper position as above described and fastening it by nails or tacks as 55 indicated at 20. This is easily accomplished and there can be no question as to the proper elevation of the sleeve and cap. Moreover, the support 15 is so strong that there can be no possibility of the pipe tilting or moving laterally after the support is attached as 60 stated. Again, plaster as indicated at 21 may be applied directly to the strip 15 the same as any other metal lath, and therefore the work of lathing and applying the plaster 65 is materially reduced and expedited. I also

indicate at 22 the expedient of applying cement or concrete directly upon the upper surface of the support 15, an expedient that as practised heretofore has required the application of shoring or other temporary support. The original cost of production of 70 this device is barely, if any, greater than the supporting means for the sleeve as heretofore practised, and, moreover, the economy and accuracy of installation thoroughly establish the superiority of the device for 75 practical purposes.

The form of the device as shown in Figs. 4 and 5 differs from that above described in that the sleeve 10' is punched along its sides 80 with pairs of holes 23 in or through which wires 15' are looped and fastened as by twisting at 24, an expedient that is rapid and cheap. The elevation of these wires above the cap, as in the other form of the 85 device, is about the same as the thickness of the lath and plaster for the ceiling.

The installation or application of this sleeve to the pipe and floor beams is in general similar to that above described. After 90 the pipe is located the sleeve is slipped up to place to an elevation easily determined to be proper and then the wires 15' are snubbed or otherwise fastened by suitable fasteners such as nails 25 driven into the 95 beams. These nails may readily be driven into the bottom edges of the beams or on the remote sides thereof from the pipe. The space around the nail heads is then covered with lath 26 and plaster 21 as indicated, or 100 any other suitable ceiling material may be applied. In both forms of the device the pipe is not only properly positioned and held in place but is free to expand or contract lengthwise of the sleeve without 105 interference with the floor construction or ceiling.

The tapering of the sleeve 10 makes it practically impossible for any dirt, cement, or other foreign matter to drop into and 110 lodge within the sleeve and therefore it is unnecessary for the upper end of the sleeve to be packed with paper, rags, or the like as is now the usual practice. Moreover, since the smaller upper end of the sleeve fits 115 practically close around the pipe, this end together with the escutcheon makes it impossible for the sleeve to tilt with respect to the axis of the pipe and therefore the cap will always maintain a proper level position 120 with respect to the other parts of the work.

I claim:

1. A device of the character described, comprising a truncated sleeve, a truncated cap on the lower end of the sleeve, the upper smaller end of the sleeve and the cap having aligned openings of the same size to fit a pipe to be positioned therethrough, and means connected to the sleeve and constituting a support therefor. 125 130

2. A device of the character described, comprising a truncated sleeve, a truncated cap on the lower end of the sleeve, the upper smaller end of the sleeve and the cap having aligned openings of the same size to fit a pipe to be positioned therethrough, and means connected to the sleeve and constituting a support therefor, said last mentioned means comprising a sheet of wire mesh having an opening therein to receive the sleeve 10 and rigidly fixed thereto.

In testimony whereof I affix my signature.

CHARLES J. PETRASEK.
